(57) **CLAIM**

The ornamental design for a cable sealing plug, as shown and described.

DESCRIPTION

The invention relates generally to cable splice enclosures, and in particular to a design for a plug useful in such enclosures.

FIG. 1 is a top view of a first embodiment of the present invention;

FIG. 2 is a bottom view of the embodiment of FIG. 1;

FIG. 3 is a front view of the embodiment of FIG. 1; FIG. 4 is a rear view of the embodiment of FIG. 1; FIG. 5 is a side view of the embodiment of FIG. 1, taken along the right side of FIG. 3; the side view taken along the left side of FIG. 3 is a mirror image of FIG. 5; FIG. 6 is a perspective view of the embodiment of FIG. 1; FIG. 7 is a cross-sectional view of the embodiment of FIG. 1, taken along the plane 7—7; FIG. 8 is a top view of a second embodiment of the present invention; FIG. 9 is a bottom view of the embodiment of FIG. 8; FIG. 10 is a front view of the embodiment of FIG. 8; the rear view is identical; FIG. 11 is a side view taken along the left side of FIG. 10; the side view taken along the right side of FIG. 10 is identical; FIG. 12 is a perspective view of the embodiment of FIG. 8; FIG. 13 is a cross-sectional view of the embodiment of FIG. 8, taken along the plane 13—13; FIG. 14 is a top view of a third embodiment of the present invention; FIG. 15 is a bottom view of the embodiment of FIG. 14; FIG. 16 is a front view of the embodiment of FIG. 14; FIG. 17 is a rear view of the embodiment of FIG. 14; FIG. 18 is a side view of the embodiment of FIG. 14 taken along the right side if FIG. 16; the opposing side view is a mirror image of FIG. 18; FIG. 19 is a perspective view of the embodiment of FIG. 14; FIG. 20 is a cross-sectional view of the embodiment of FIG. 14 taken along the plane 20—20; FIG. 21 is a top view of a fourth embodiment of the present invention; FIG. 22 is a bottom view of the embodiment of FIG. 21; FIG. 23 is a front view of the embodiment of FIG. 21; the rear view is identical; FIG. 24 is a side view of the embodiment of FIG. 21 taken along the right side of FIG. 23; the side view taken along the left side of FIG. 23 is identical; FIG. 25 is a perspective view of the embodiment of FIG. 21; and, FIG. 26 is a cross-sectional view of the embodiment of FIG. 21 taken along the plane 26—26.
